VENTILATED SPOKE-WHEEL BUFF

Henry H. Bahr, New York, N. Y., assignor to
 Guaranteed Buff Co., Inc., New York, N. Y., a
 corporation of New York

Application December 16, 1948, Serial No. 65,621

10 Claims. (Cl. 51—193)

1

The present invention is directed to buffing wheels, more particularly to an improved construction of such wheels whereby long life and adequate ventilation during operation are obtained.

In my co-pending application, Serial No. 34,574, filed June 22, 1948, which issued as Patent No. 2,559,385, dated July 3, 1951, and entitled "Construction of Buffing Wheel," I have described and claimed a buffing wheel in which a roll of fabric containing a plurality of layers is folded on itself to form a cylindrical roll and metal pieces are introduced into the fold and extending below the same. The free ends of said metal pieces are anchored in a suitable base which may be of disk or annular form whereby the roll of fabric is formed into a series of folds with a space between the base and the inner edge of the fabric to provide ventilation. Such a construction has been found to be practical and to have a long life. However, further development of the type of structure shown in said application for patent has been made and improved buffing wheels have been produced.

It is among the objects of the present invention to provide a buffing wheel of the general type described above, in which the means for mounting are simple and effective to hold the fabric in its proper position without danger of displacement.

It is also among the objects of the present invention to provide a structure of the type described in which a plurality of folded sets of fabric may be mounted on a single base to provide a relatively wide and/or more uniform buffing face.

In practicing the present invention, there is provided a base which is usually a disk having a central opening for mounting on a suitable shaft. A roll of bias cut fabric is produced by winding a sheet of fabric into a cylinder with a predetermined number of turns and then folding the roll of fabric on itself at approximately its transverse centerline, thus doubling the number of layers or plies of fabric. A series of openings of suitable size and shape are made in the fold of the roll for the passage of suitable metal or other pieces which act as mounting means for the fabric on the base. The metal pieces are preferably made of wire, usually circular in cross-section and bent so as to be in the shape of a series of inverted U's, the legs of which are bent to form hooks or the like. Each of the pieces is inserted through a pair of openings in the roll with the hooks extending below the same. A

2

series of holes are provided near the periphery of the disk and the hook members are introduced into the holes and clamped in position. Usually a line of stitching is provided just above the fold in the fabric, either before or after the wire pieces are inserted, in order to prevent movement of the fabric with relation to the metal pieces and the friction resulting from such movement. Variations of such structures are contemplated.

10 In the accompanying drawing constituting a part hereof, and in which like reference characters indicate like parts:

Fig. 1 is a side elevational view of a buffing wheel made in accordance with the present invention, some of the parts being broken away for clearness;

Fig. 1-a is a fragmentary cross-sectional view taken through the metal pieces of Fig. 1;

Fig. 2 is a vertical cross-sectional view of an assembly of a plurality of buffing wheels on a shaft and adapted for operation, some parts being shown in elevation and other parts being broken away;

Fig. 3 is a perspective view of a folded cylindrical roll of fabric prior to mounting the same on the base;

Fig. 4 is a view similar to Fig. 1, showing a somewhat modified form of the invention;

Fig. 5 is a fragmentary perspective view of a portion of the base showing the manner in which the U-shaped metal pieces are anchored therein;

Fig. 6 is a fragmentary elevational view taken along the line 6—6 of Fig. 4;

Fig. 7 is a view similar to Fig. 4, showing a still further modification of the invention;

Fig. 8 is an elevational view taken along the line 8—8 of Fig. 7;

Fig. 9 is a fragmentary perspective view of Fig. 7, showing the manner in which the U-shaped metal pieces are anchored in the base;

Figs. 10, 11 and 12 are fragmentary perspective views of the roll of fabric showing the folded edge thereof and illustrating various arrangements and openings for mounting the U-shaped pieces therein, and

Fig. 13 is a fragmentary perspective view of a further modified form.

Referring to the modification shown in Figs. 1 to 3, the base consists of a disk 1 mounted on a shaft 2 and having a series of closely spaced holes 3 near the periphery thereof. A strip of bias cut fabric 4 is rolled into a cylinder of one or more layers and folded at 5 to form a double number of layers of fabric presenting the free edges of said fabric to articles to be buffed. A

series of openings 6 are formed along the fold 5 through all of the layers of fabric, the size and shape of said openings being of any desired type suitable for the purpose. There are provided a series of metal pieces 7 usually formed from round wire, having a pair of legs with a connecting portion, the legs extending through pairs of openings 6 and the connecting portion contacting with the inner side of fold 5, thereby holding the fabric with respect to the metal pieces 7. Usually the metal pieces are first inserted into opening 6, as shown in Fig. 3, and then a line of stitching 8 is provided just above said pieces in order to prevent accidental displacement thereof. In some cases the line of stitching may be first made and the metal pieces inserted into the pairs of openings 6 thereafter.

The roll of Fig. 3 is then mounted on base 1 as shown in Fig. 1. A metal member having legs 9 and 10 and connecting portion 11 has leg 9 inserted in a hole 3 and the hook 12 thereof bent to anchor it in position. At the same time, leg 10 is inserted in a hole 3 spaced from the first-mentioned hole by two intervening holes and hook 12 bent to clamp the leg 10 in position. Another metal member having legs 9' and 10' is similarly mounted with leg 9' in the hole 3' adjacent to leg 10, and leg 10' in the hole 3' one removed from leg 10. The next adjacent metal member has legs 9'' and 10'' mounted in holes 3'' adjacent to legs 9' and 10', respectively. Similarly, the other metal members are anchored all around the periphery of base 1. Each of the metal members is bent so that the connecting portions 11, 11, etc. are in a plane at an angle to the plane of disk 1. Thereby the folds 13 of fabric 4 are at an angle to the plane of said disk. This spreads the buffing surface over a considerable area, many times greater than the thickness of the fabric when flat. Thus a highly satisfactory buffing surface is formed.

In mounting a plurality of buffing wheels for use on a shaft as shown in Fig. 2, the shaft is provided with a shoulder 14 and a flange 15 having a diameter approximately equal to the diameter of disk 1 is mounted on the shaft and in contact with said shoulder. Then a buffing wheel is mounted in contact with flange 15. A spacer disk 16 of the same diameter is placed against the opposite face of the mounted buffing wheel and a second buffing wheel mounted against the opposite face of spacer 16. An outer flange 17 is then placed against the outer face of the second buffing wheel and a nut 18 is tightened on the shaft to form a buffing unit having two buffing wheels operating as a single unit. Elements 15 and 16 have a vise-like clamping action on the disks and hooks. A single wheel may be thus mounted or a greater number may be placed on the shaft as required. The spacer may be of such thickness that the fabrics 4 of the wheels are spaced apart and just touch each other or the plurality of wheels may be so mounted that the folds 13 of one buffing wheel interlock with the folds of an adjacent buffing wheel, thus forming a more solid fabric buffing surface.

In the modification shown in Figs. 4, 5 and 6, the base is a disk 1 having openings 3 but the fabric is mounted on the U-shaped metal members in a different manner. A roll of fabric is formed as shown in Fig. 3, and if desired the metal pieces may be mounted therein before stitching is resorted to. The spacing of the pairs of openings in the fabric at fold 5 is wider than the distance between legs of the metal

pieces 7, thus forcing the fabric to form ruffles. This way, instead of providing folds 13 in the fabric, the roll is ruffled to form ruffles 20, and a line of stitching 21 holds the ruffles in position. The fabric containing the metal pieces is mounted on disk 1, as shown more particularly in Fig. 5, with the plane of the metal pieces being adjacent to and practically coinciding with the plane of disk 1. In the structure of Fig. 4 the number of holes 3 may be reduced to accommodate only the metal members as shown in said figure.

In the modification shown in Figs. 7, 8 and 9, a roll of fabric such as that shown in Fig. 4, is provided and is similarly mounted. A second roll of fabric 4' similarly mounted on U-shaped metal pieces and the like is mounted on disk 1. The mounting of fabric 4' is from the opposite side of the disk. As shown in Fig. 7, metal pieces 22 of fabric 4' have the hooks thereof extending from the back of disk 1 and onto the face thereof. Metal pieces 23 of fabric 4 enter holes 3 on the face of disk 1 and the hooks are bent around at the back thereof. In this modification the fabrics 4 and 4' may be in actual contact with each other or the metal pieces of the fabric 4 may be bent to one side of the plane of disk 1 as shown in Fig. 7 and the metal pieces of fabric 4' may be bent to the other side of the plane of said disk as shown in Fig. 7, whereby the fabrics are spread somewhat apart and provide a relatively wider face for buffing purposes, and a greater circulation of air.

In place of the ruffling as shown in Fig. 4, the gathering or ruffles may be formed by the spacing of the openings at the fold of the roll of fabric. In Fig. 10 there is shown a series of openings 24, 25, 26 and so on all around the roll of fabric. These openings are equally spaced and the distance between them is greater than the distance between the legs of a metal piece as shown to the left of Fig. 10. When the legs of a piece are introduced into openings 24 and 25, it automatically causes a ruffling or wrinkling of the fabric so that the effect shown in Fig. 4 is thus obtained. If the holes are spaced equal to the distance between said legs, then the ruffles are formed between the adjacent metal members.

A further modification of the spacing of the openings is shown in Fig. 11. A pair of openings 27 and 28 is provided, the distance between them being greater than the distance between the legs of a metal piece. There is provided a pair of auxiliary openings 29 between openings 27 and 28 so that the connecting portion of metal piece 7 may be threaded through openings 29 and then inserted in opening 28. By this arrangement, the same wrinkling or ruffling effect is obtained as in Fig. 10 but the fabric is held more surely against displacement by the intermediate threaded portion. The adjacent sets of openings are similar to those just described and the opening 28 of one set is relatively closely spaced from opening 27 of the adjacent set in order to minimize the portion of the roll of fabric which is not ruffled.

In the modification shown in Fig. 12, the pairs of openings 35 and 36 of one set are quite close to opening 30 of the adjacent set as so to minimize the unruled portion of the fabric roll.

There are a number of advantages inherent in the present structure in that because of the relatively small diameter of the wire, a relatively small portion of the space between the fabric 75 and the base is occupied, leaving more space for

the in-flow of air and thus the ventilating effect is increased. Because the wire is usually round or in any case does not have sharp corners, the connecting portion of the metal pieces will not cut into the fabric and thus a more secure holding of the fabric is obtained. The legs of the wire pieces being anchored at two separated points on the base give a wider base to the mounting, which increases the stability of the structure and minimizes any tendency for relative movement between the fabric and the base. The use of wire greatly decreases the cost of production in that there is no waste, and the wire may be cut off and readily bent to the proper shape on standard automatic machines. By the use of a U-shaped metal piece, the labor involved in assembling the buffering wheel is simplified. The anchoring of the metal pieces on the base may be accomplished by a single operation, thus reducing the labor involved in the operation. Because of the rounded surfaces of the wire, dust or lint is not easily deposited on such surface and thus there is less danger of a stoppage of the flow of air due to clogging of the wires. The use of flanges on the sides of the buffering wheel to mount the same on a shaft provides greater strength and more rigidity in operation.

Although the invention has been described setting forth several specific embodiments thereof, the invention is intended to be broad and the several modifications are intended to illustrate the breadth of the invention. Various changes in the details may be made within the spirit of the invention, as for example the size and shape of the spacers between the multiple buffering wheels may be varied in order to give desired effects. The base need not be a simple disk but other forms of bases may be used, strengthening ribs may be formed therein and flat rims may be provided thereon, if desired. Elements may be added to the structure, as for example in order to supplement the stitching of the fabric to hold the metal pieces in their proper positions or even in place thereof, clips may be pressed over the folded end of the fabric roll and over the connecting portion of the metal pieces to grip the latter and prevent the movement thereof relative to the fabric. Such clips may be individual members for each metal piece or a continuous strip of material bent over and clamped at suitable intervals may be used. Eyelets may be provided in openings 6 to add strength to the assembly.

The buffering surface may be made up of a series of folded or ruffled fabric units, each mounted on one or more metal members secured to the disk. Or one small doubled-up roll of fabric may be mounted on one or more metal members, and a series thereof secured to the disk. Instead of the hooks on the metal members and holes in the disk, the ends of the legs may be welded or otherwise secured to the face of the disk; or two disks may be provided with the ends of the legs clamped between them, and such ends may have heads fitting into recesses or holes in the disks to anchor the metal members; and all these structures are considered to be the mechanical equivalent of the hook-and-hole arrangement.

Combinations of several of the features of the various modifications may be made, such a combination being shown in Fig. 13 in which the effect of the two pieces of fabric of Fig. 7 is combined with the fold arrangement of Fig. 1. In this case the roll of fabric is made larger than in Fig. 1 and it is associated with U-shaped hooks 7 so as to provide folds 32 at one side of

the plane of disk 1 with the hooks entering said side, and alternate folds 33 at the other side with the hooks entering said other side.

I claim:

1. A buffering wheel comprising a disk-like hub, a single cylindrical roll of fabric doubled up along its center periphery and having a plurality of sets of openings in said doubled up portion, U-shaped metal members each having a substantially flat base and a pair of legs, said legs passing through said openings and said base being held in said doubled up portion, said hub having holes at its periphery, the ends of said legs having hooks thereon, said hooks passing through said holes, the distance between said members in said fabric being greater than the distance between the sets of holes into which the hooks of said members pass, whereby loose radial ruffles are formed in said fabric.
2. A buffering wheel comprising a disk-like hub, a single cylindrical roll of fabric doubled up along its center periphery and having a plurality of sets of openings in said doubled up portion, U-shaped metal members each having a substantially flat base and a pair of legs, said legs passing through said openings and said base being held in said doubled up portion, said hub having holes at its periphery, the ends of said legs having hooks thereon, said hooks passing through said holes, the distance between said members in said fabric being greater than the distance between the sets of holes into which the hooks of said members pass, whereby loose radial ruffles are formed in said fabric, the inside edge of said fabric being spaced from the periphery of said hub to provide air-passage into said ruffles.
3. A buffering wheel comprising a disk-like hub, a single cylindrical roll of fabric doubled up along its center periphery and having a plurality of sets of openings in said doubled up portion, U-shaped metal members each having a substantially flat base and a pair of legs, said legs passing through said openings and said base being held in said doubled up portion, said hub having holes at its periphery, the ends of said legs having hooks thereon, said hooks passing through said holes, the distance between said members in said fabric being greater than the distance between the sets of holes into which the hooks of said members pass, whereby loose radial ruffles are formed in said fabric, the hooks of each member passing through non-adjacent holes with at least two intervening holes.
4. A buffering wheel comprising a disk-like hub, a single cylindrical roll of fabric doubled up along its center periphery and having a plurality of sets of openings in said doubled up portion, U-shaped metal members each having a substantially flat base and a pair of legs, said legs passing through said openings and said base being held in said doubled up portion, said hub having holes at its periphery, the ends of said legs having hooks thereon, said hooks passing through said holes, the distance between said members in said fabric being greater than the distance between the sets of holes into which the hooks of said members pass, whereby loose radial ruffles are formed in said fabric, the plane passing through said base being at an angle to the plane of said hub and said ruffles being at said angle.
5. A buffering wheel comprising a disk-like hub, a single cylindrical roll of fabric doubled up along its center periphery and having a plurality of sets of openings in said doubled up portion, U-shaped metal members each having a substan-

tially flat base and a pair of legs, said legs passing through said openings and said base being held in said doubled up portion, said hub having holes at its periphery, the ends of said legs having hooks thereon, said hooks passing through said holes, the distance between said members in said fabric being greater than the distance between the sets of holes into which the hooks of said members pass, whereby loose radial ruffles are formed in said fabric, the plane passing through said members being substantially parallel to the plane of said hub and said ruffles being parallel thereto.

6. A buffing wheel comprising a disk-like hub, a single cylindrical roll of fabric doubled up along its center periphery and having a plurality of sets of openings in said doubled up portion, U-shaped metal members each having a substantially flat base and a pair of legs, said legs passing through said openings and said base being held in said doubled up portion, said hub having holes at its periphery, the ends of said legs having hooks thereon, said hooks passing through said holes, the distance between said members in said fabric being greater than the distance between the sets of holes into which the hooks of said members pass, whereby loose radial ruffles are formed in said fabric, the plane passing through said members being substantially parallel to the plane of said hub and said ruffles being parallel thereto, alternate ruffles being on opposite sides of said hub plane.

7. A buffing wheel comprising a disk-like hub, a single cylindrical roll of fabric doubled up along its center periphery and having a plurality of sets of openings in said doubled up portion, U-shaped metal members each having a substantially flat base and a pair of legs, said legs passing through said openings and said base being held in said doubled up portion, said hub having holes at its periphery, the ends of said legs having hooks thereon, said hooks passing through said holes, the distance between the legs of each member being less than the spacing of the corresponding openings in said fabric, whereby loose radial ruffles are formed in said fabric.

8. A buffing wheel comprising a disk-like hub, a single cylindrical roll of fabric doubled up along its center periphery and having a plurality of sets of openings in said doubled up portion, U-shaped metal members each having a substantially flat base and a pair of legs, said legs passing through said openings and said base being held in said doubled up portion, said hub having holes at its periphery, the ends of said legs having hooks thereon, said hooks passing through said

holes, the distance between the legs of each member being less than the spacing of the corresponding openings in said fabric, whereby loose radial ruffles are formed in said fabric, the plane passing through said members being substantially parallel to the plane of said hub.

9. A buffing wheel comprising a disk-like hub, a single cylindrical roll of fabric doubled up along its center periphery and having a plurality of sets of openings in said doubled up portion, U-shaped metal members each having a substantially flat base and a pair of legs, said legs passing through said openings and said base being held in said doubled up portion, said hub having holes at its periphery, the ends of said legs having hooks thereon, said hooks passing through said holes, the distance between the legs of each member being less than the spacing of the corresponding openings in said fabric, whereby loose radial ruffles are formed in said fabric, the plane passing through said members being substantially parallel to the plane of said hub, a second similar roll, said rolls being mounted on opposite sides of said hub.

10. A buffing wheel comprising a disk-like hub, a single cylindrical roll of fabric doubled up along its center periphery and having a plurality of sets of openings in said doubled up portion, U-shaped metal members each having a substantially flat base and a pair of legs, said legs passing through said openings and said base being held in said doubled up portion, said hub having holes at its periphery, the ends of said legs having hooks thereon, said hooks passing through said holes, the distance between the legs of each member being less than the spacing of the corresponding openings in said fabric, whereby loose radial ruffles are formed in said fabric, auxiliary openings in said doubled up portion, said bases being threaded through said auxiliary openings.
